ATTORNEY

UNITED STATES PATENT OFFICE.

FLAMINIO F. MEYRELLES, OF WEST SOMERVILLE, MASSACHUSETTS.

STOPPER.

Specification of Letters Patent. Patented Feb. 11, 1919.

1,293,854.

Application filed May 28, 1918. Serial No. 237,023.

To all whom it may concern:

Be it known that I, FLAMINIO F. MEYRELLES, a citizen of Portugal, residing at West Somerville, in the county of Middlesex and State of Massachusetts, U. S. A., have invented certain new and useful Improvements in Stoppers, of which the following is a specification.

This invention relates to stoppers, and 10 more particularly to a cork stopper especially adapted for use in connection with bottles and similar containers.

One of the main objects of the invention is to provide a stopper of simple construction and operation provided with a gripping member to facilitate extraction of the stopper from a bottle neck.

A further object is to provide a simple and efficient means which may be readily 20 applied to a cork stopper of standard construction at very small cost, and so connected thereto as to prevent damage to the stopper when being extracted.

A further object is to provide means of 25 the character above stated which may be produced at a very small cost.

Further objects will appear from the detailed description.

In the drawings:

30 Fig. 1, is a side view of a stopper constructed in accordance with my invention.

Fig. 2, is a central vertical section through the same.

Fig. 3, is a detail perspective of the gripping member.

Fig. 4, is a side view of a modified form of the invention.

Fig. 5 is a central vertical section through the form illustrated in Fig. 4.

40 Fig. 6, is a perspective detail, with the elements disassembled, of the gripping member employed in connection with the form illustrated in Figs. 4 and 5.

The cork stopper 1 is of usual shape and 45 construction, and is provided in its lower or smaller end portion with a central substantially cylindrical recess which is closed by a plug 2 which may be formed from cork secured in the recess by water proof cement, or any other suitable material such as rubber, gum, etc. A sheet metal disk 3 is mounted in the upper end of the recess 2^a which receives the plug 2, and is provided with a central aperture through 55 which is inserted the shank 4 of a gripping member indicated generally by 5. The

shank 4 is provided, at its lower end, with an integral head 6 which serves to effectually prevent detachment of the member 5 from disk 3. This member 5 may be 60 formed by bending from a suitable length of wire the upper portion of which is bent to form the loop 7 adapted to receive any suitable instrument inserted therethrough for facilitating extraction of the cork. The 65 disk 3 is provided with two integral diametrically opposite teeth or points 8 which engage into the body of the stopper 1 so as to effectually prevent displacement of the disk. The teeth also serve to prevent turning 70 of the disk by turning of member 5 thus eliminating all possibility of the disk being loosened in the recess 2^a.

In the form illustrated in Figs. 4, 5 and 6, the stopper 9 is provided, at the central 75 portion of its lower end with a substantially cylindrical recess 10 which is adapted to be closed by a plug 11 fixedly secured therein. A disk 12 is mounted in the upper end of the recess and is provided with diametrically opposite notches 13. These notches receive the spaced arms 14 of a substantially rectangular gripping member 15, the lower end bar 16 of which passes beneath the disk 12 the upper end of the arms 14 80 being twisted together as at 17. As will be noted clearly from Figs. 2 and 5, member 15 projects above the upper end of the stopper 1^a so as to provide a substantially semi-circular loop 18 which is adapted to 85 receive a suitable instrument inserted therethrough to facilitate the extraction or removal of the stopper from the neck of a bottle or similar container.

In both forms of the device, the stopper 95 may be readily removed from the neck of the bottle into which it has been inserted by placing a suitable instrument through the loop of the gripping member and then exerting outward pull on the member. This 100 enables the cork to be easily removed and the stopper thus constructed may be readily used in connection with a bottle or similar container of standard construction. Also, in view of the fact that the recess in which 105 the reinforcing disk for the gripping member is mounted is completely closed by the plug inserted thereinto, all danger of injury to the contents of the container by contact with this disk or the gripping member is effectually eliminated.

The foregoing description and the draw-

ings have reference to what may be considered the preferred, or approved form of invention, it is understood that I may make such changes in construction and arrangement and combination of parts, materials, dimensions, etc., as may prove expedient and fall within the scope of the appended claim.

Having thus described my invention what I claim as new and desire to secure by Letters Patent is:

In a device of the class described, a stopper provided in its lower end with a recess, a disk seated in said recess and notched in opposite edges, a wire extracting element

having parallel arms projecting from the 15 recess through the stopper and connected at their upper ends, and a cross bar connecting their lower ends across the bottom of said disk, the arms standing in said notches, and a plug closing said recess beneath the 20 disk and grooved across its upper end to receive said cross bar.

In testimony whereof I affix my signature in presence of two witnesses.

FLAMINIO F. MEYRELLES.
